his Atty.

UNITED STATES PATENT OFFICE.

FREDERICK B. RAND, OF SANFORD, MAINE.

LUG-STRAP HOLDER.

1,327,964.

Specification of Letters Patent. Patented Jan. 13, 1920.

Application filed October 6, 1919. Serial No. 328,826.

To all whom it may concern:

Be it known that I, FREDERICK B. RAND, a citizen of the United States, and resident of Sanford, county of York, State of Maine, have invented an Improvement in Lug-Strap Holders, of which the following description, in connection with the accompanying drawings, is a specification, like characters on the drawings representing 10 like parts in each of the several views.

This invention relates to loom attachments and more particularly to an improved lug strap holder adapted to be adjustably applied to the picker staff of a loom. A 15 principal object of the invention is to provide a simple and cheaply made lug strap holder that is adapted to be clamped to the picker staff adjustably according to the power requirements and in a manner so as 20 to reinforce the picker staff instead of weakening it. To this end I provide a backing piece of wood adapted to be adjustably clamped to the picker staff and having a metallic wear piece associated therewith and 25 co-operative with the clamping member. This backing piece is also equipped with spaced apart transverse inserted pins adapted 30 to hold between them the lug strap, the backing piece thus produced requiring a minimum of material and little finishing work, and the transverse pins being quickly 35 and easily applied or renewed in case of breakage. The foregoing and other objects and advantages of the invention will more 40 fully appear from the following detailed description, and the distinctive features of novelty will be pointed out in the appended claims.

Referring to the drawings:

40 Figure 1 is a perspective view showing a fragmentary portion of a loom frame with the picker staff thereof equipped with my invention;

45 Fig. 2 is a detail side elevation showing a portion of the picker staff with my improved lug strap holder applied thereto;

Fig. 3 is a vertical section on line 3—3 of Fig. 2; and

50 Fig. 4 is a detail section on line 4—4 of Fig. 3 on a larger scale.

10 indicates a fragmentary portion of the frame work of a loom and 11 indicates a picker staff which may be of usual type mounted to swing from its lower end at 12 55 by a usual or suitable mounting. 13 indi-

cates the picker sweep having connected therewith a lug strap 14 as usual. In accordance with my invention I provide a piece 15 preferably of wood and approximately ten inches or thereabouts in length. 60 This piece of wood may be approximately square in cross section with somewhat rounded edges at an intermediate portion 15^a where it is engaged by the lug strap. The upper part of this piece has fixed transversely therethrough pins 16, 17 spaced apart to receive and hold between them the lug strap 14 with a capability of easy movement and self-adjustment with respect to the picker staff as it actuates the same. The 70 lower portion of this piece 15 has a hole 18 therethrough in which engages a stud 19 projecting from a backing and wear plate 20. The plate 20 has its sides recessed as indicated at 21 to receive the 75 sides of a metallic clamp yoke 22 through which extends the picker staff 11 as well as the piece 15 mounted at the back thereof. The yoke 22 is equipped with a clamping screw 23 equipped with a usual lock nut 80 24. On setting up this screw it engages with a wear seat 20^a of the plate 20 and clamps this plate firmly against the piece 15, the piece 15 being in turn securely clamped to the picker staff by the clamping 85 action of the screw. The plate 20 is equipped with projections 20^b at each side of the recesses 21 which are adapted to hold the yoke 22 properly located with reference thereto. It will be noted that by merely 90 loosening the screw 23, the piece 15 may be adjusted along the picker staff so as to properly position the lug strap thereon according to the power requirements. It is to be further particularly noted that the present lug strap holder may be very simply and cheaply made since the wood piece 15 may be a plain square stick merely bored to receive the pins 16, 17 that may be driven and glued therein, and also bored 95 to receive the stud 19, requiring no other finishing or work thereon whatever. The backing and wear plate 20 is likewise a simply and cheaply produced member and the engagement of the stud 19 with the 100 stick 15 holds this member properly assembled therewith while the engagement of the yoke 22 between the lugs or projections 20^b holds the parts properly assembled with the yoke and with the picker staff. I con- 105 110

sider the described construction and arrangement permitting the use of this plain square stick 15 for the holder to be of special value and importance, since so far as known to me devices of this general character heretofore proposed have required a relatively elaborate fashioning of the holder, and when a corresponding piece of wood has been employed it has required considerable finishing and work thereon to reduce it to the necessary shape for service. I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having described my invention, what I claim as new and desire to secure by Letters Patent is:

1. A lug strap holder, comprising a stick adapted to be clamped to the back of a picker staff, said stick having spaced apart

pins fixed transversely therethrough to hold between them the lug strap, and a yoke equipped for clamping said stick to the picker staff.

2. A lug strap holder, comprising a stick generally square in cross section having spaced apart pins transversely fixed therein to hold between them the lug strap, a clamp for securing said stick to the picker staff, and a wear plate associated with said stick and held assembled with said clamp to be engaged thereby.

3. A lug strap holder, comprising a stick equipped with spaced apart pins to hold between them a lug strap, a yoke equipped with a clamping screw for adjustably securing said stick to a picker staff, and a wear plate having a stud socketed in said seat and equipped with projections to hold the same assembled with said yoke whereby it is engaged by said clamping screw to clamp the stick to the picker staff.

In testimony whereof, I have signed my name to this specification.

FREDERICK B. RAND.
